AUTOMATIC CONTROL OF TELEVISION RECEIVING SYSTEMS

John C. Wilson, Bayside, N. Y., assignor to Hazeltine Corporation, a corporation of Delaware

Application March 15, 1938, Serial No. 195,955

10 Claims.

(CL 178—7.3)

This invention relates to television receiving systems and, more particularly, to the automatic control of one or more operating characteristics of such systems in accordance with the amplitude characteristics of received signals. The invention is especially directed to the provision of an improved automatic amplification control system for television receivers.

In accordance with present television practice, a transmitted signal comprises a carrier which is modulated during successive intervals or trace periods by high-frequency and unidirectional components representative of an image being transmitted and of its average background illumination, respectively, and is modulated between the trace periods, that is, during retrace intervals, by synchronizing components which correspond to initiations of successive lines and fields in the scanning of the image.

At the receiver, a beam is so deflected as to scan and illuminate a target in a series of fields of parallel lines. The synchronizing components of the received signal are utilized to control the scanning apparatus of the receiver so as to synchronize its operation with that of similar apparatus utilized at the transmitter in developing the signal. The intensity of the beam is controlled by the light-modulation components, thereby to reconstruct the image.

In certain proposed television systems, the video-frequency modulation developed from the image is so impressed on the carrier that increases in the carrier amplitude correspond to increases in brightness of the image, this being termed positive modulation; the background illumination is transmitted directly, that is, by variation of the average carrier intensity during the trace intervals directly in accordance with the low-frequency or steady background light variations. Between trace periods, a blanking signal is transmitted which corresponds in amplitude to black or blacker than black and establishes a predetermined blanking level. The synchronizing pulses are impressed on the carrier during the blanking intervals in the opposite sense to the light-modulation signals, ordinarily periodically reducing the carrier amplitude to zero.

While systems utilizing the type of signal just mentioned have, in general, given satisfactory results, they have been objectionable in that it has been difficult or impossible heretofore to provide satisfactory automatic control of the system characteristics in accordance with the average received carrier amplitude and independent of light modulation, as, for example, automatic

amplification control. More particularly, since the average intensity of the carrier is varied in accordance with background light-modulation components, neither the average nor the peak carrier intensity can be utilized to effect satisfactory automatic amplification control in the conventional manner, which requires some controlling effect dependent solely upon the average carrier intensity as determined by the power of the transmitting station, its distance, fading, etc., and independent of the degree of modulation. Nor can the amplitude of the synchronizing pulses of such a signal be made readily available for this purpose, as it can in the case of negative modulation where these pulses are transmitted on outward peaks of modulation at a relatively fixed amplitude, since, in positive-modulation systems, the synchronizing pulses are ordinarily transmitted on inward peaks of modulation corresponding substantially to zero amplitude of the carrier wave. Various arrangements have, however, been devised heretofore for providing an automatic control of an operating characteristic of a positive-modulation television system in accordance with the average amplitude of received carrier wave and independent of light modulation. In general, however, these systems have been objectionable in that they were dependent upon precise timing impulses, making their operation highly critical.

It is an object of the present invention, therefore, to provide a television receiver including improved means for automatically controlling one or more operating characteristics of the receiver in accordance with the average intensity of the received modulated-carrier signals and independently of the light-modulation components.

It is a further object of the invention to provide an improved automatic amplification control system for television receivers adapted for the reception of positively-modulated television signals including background and high-frequency light-modulation components.

It is a further object of the invention to provide a system of the character described which operates independently of any timing impulses.

In accordance with the present invention, a television receiver adapted for the reception of positively-modulated television signals, including background components, synchronizing components, and video-frequency light-modulation components, comprises asynchronous control means responsive to a predetermined intermediate amplitude level of the modulation envelope of the signals, and including a time-constant cir-

cuit for substantially eliminating the effect of said synchronizing components on the output thereof for developing a controlling effect. Means are further provided for utilizing this controlling effect for adjusting an operating characteristic of the receiver.

In a preferred embodiment of the invention, a television receiver comprises means for detecting the signal to derive the modulation envelope, which means may be a conventional diode rectifier. A stabilizer is preferably coupled to the output circuit of the detecting means for establishing a fixed level for the peaks of the synchronizing pulses and developing a signal component varying in accordance with the blanking level of the modulation envelope. Suitable rectifying means, for example, a diode rectifier, is provided for developing a unidirectional control-bias voltage from the peak value of the voltage representing the difference between the stabilized detected signal and a fixed voltage. The unidirectional voltage thus developed may be utilized to control the amplification in various stages of the system, thereby to maintain the signal-output intensity within a relatively narrow range for a wide range of signal-input intensities.

For a better understanding of the present invention, together with other and further objects thereof, reference is had to the following description taken in connection with the accompanying drawings, and its scope will be pointed out in the appended claims.

In the accompanying drawings, Fig. 1 is a circuit diagram, partially schematic, of a cathode-ray tube television receiving system including circuits embodying the present invention; Fig. 2 is a diagrammatic illustration of a positively-modulated television carrier wave, to aid in the understanding of the invention, while Figs. 3, 4, 5, and 6 are groups of wave forms representing the derived signal developed at different points in the receiver of Fig. 1.

Referring now more particularly to the drawings, the system there illustrated comprises a receiver of the superheterodyne type including an antenna and ground system 10-11 connected to a radio-frequency amplifier 12 to which is connected in cascade, in the order named, an oscillator-modulator 13, an intermediate-frequency amplifier 14, a detector 15, a video-frequency amplifier 16, and a cathode-ray signal-reproducing tube 17. A line-frequency generator 18 and a field-frequency generator 19 are also coupled to the video-frequency amplifier and connected to the scanning elements of the cathode-ray tube in the conventional manner. The stages or units 10-19, inclusive, may all be of conventional well-known construction so that detailed illustrations and descriptions thereof are deemed unnecessary herein.

Referring briefly, however, to the operation of the system described above, television signals intercepted by the antenna circuit 10-11 are selected and amplified in the radio-frequency amplifier 12 and supplied to the oscillator-modulator 13, where they are converted to intermediate-frequency signals which, in turn, are selectively amplified in the intermediate-frequency amplifier 14 and delivered to the detector 15. The modulation components of the signal are derived by the detector 15 and are supplied to the video-frequency amplifier 16 wherein they are amplified and from which they are supplied in the usual manner to a brilliancy-control electrode of the cathode-ray tube 17 and to the synchronizing-

control elements of the generators 18 and 19. The intensity of the electron beam of the tube 15 is thus modulated or controlled in accordance with the video-frequency voltages impressed upon the control electrode of the tube in the usual manner. Saw-tooth current or voltage-scanning waves are generated in the line- and field-frequency generators 18 and 19, which are controlled by synchronizing-voltage impulses supplied from the video-frequency amplifier 16, and applied to the scanning elements of the cathode-ray tube 17 to produce electric scanning fields, thereby to deflect the ray vertically and horizontally so as to trace a rectilinear scanning pattern on the screen of the tube and thereby reconstruct the transmitted picture.

Referring now more particularly to the portion of the system of Fig. 1 embodying the present invention, for the purpose of developing a control-bias voltage there is provided an asynchronous control means including a vacuum-tube repeater 20 connected to act as a stabilizer, a rectifier 21, and a direct current reversing amplifier 22, as shown, which is responsive to a predetermined intermediate amplitude level of the received signal. The tube 20 may be of any suitable type having an input circuit, comprising a coupling condenser 23 and leak resistor 24, connected to the output circuit of the detector 15. An output circuit is provided for the tube 20 comprising a resistor 25 and a parallel condenser 26 having a predetermined time constant which is long compared to the duration of the line-synchronizing pulses and blanking intervals, but short compared to the field blanking intervals. For conventional systems utilizing, for example, 30 frames of 441 lines per second, the resistor 25 may be of the order of 100,000 ohms and the condenser 26 of the order of 0.006 microfarad, providing a time constant of 0.0006 second. The diode rectifier 21 is coupled across the output circuit of the tube 20 and is provided with a load circuit comprising a parallel-connected resistor 27 and condenser 28 having a large time constant. This time constant should be considerably greater than the field-scanning period, which may, for example, be $\frac{1}{60}$ second, in which event the time constant may be of the order of $\frac{1}{6}$ second. The input electrodes of the reversing amplifier are connected across the resistor 27, while its anode circuit includes a load resistor 29. Operating potentials are applied to the anodes of the tubes 20 and 22 by way of their respective resistors 25 and 29 from suitable sources, indicated at +B. The less positive end of the resistor 29 is connected, by way of a suitable filter including series resistors 30 and shunt condensers 31 and conductors 32, to the control electrodes of one or more vacuum tubes included in the amplifier 12, oscillator-modulator 13, and amplifier 14, as shown. The lead 32 may include a negative-biasing battery 33 to compensate for the high potential of the anode of the tube 22 from which the volume control potential is derived. However, if the cathodes of the tubes in the stages 12, 13, and 14 are properly biased the battery may be omitted.

The operation and results obtained by the system of Fig. 1 may best be understood by reference to Figs. 2-6, inclusive. In Fig. 2 there are illustrated the wave forms of portions of the complete modulation envelopes of television carrier waves of the positively-modulated type. The portion shown at A represents a wave of relatively great amplitude while that at A' represents a similar wave differing only in that it is of

lesser amplitude, as might be caused by occasional fading. In Figs. 3-6, inclusive, corresponding wave portions are shown, illustrating the form of the signal derived at different parts of the system.

The points of the wave of Fig. 2 at which the carrier amplitude is reduced to zero, certain of which are indicated at L, represent line retrace periods or synchronizing pulses. The portions between the pulses L correspond to the trace portions of successive lines and are modulated, as indicated at M₁ and M₂, by the high-frequency and background light components. During the frame retrace periods, part of one of which is indicated at Y-Y, the amplitude of the wave is independent of light modulation. The frame retrace periods ordinarily include the line pulses, as well as additional broad pulses, not shown, which latter constitute collectively a frame-synchronizing pulse.

It is well known that, with the positive type of modulation, such as is represented in Fig. 2, increases in light intensity of the image being scanned are represented by increases in the amplitude of the carrier amplitude and the average intensity of the signal is varied in accordance with the low-frequency or unidirectional background-illumination components of the image. Thus, in the particular portions of the wave shown, during the line-trace modulation periods represented at M₁, the amplitude of the carrier is such that it reaches the white level, whereas this does not occur during the modulation periods represented at M₂. Since the average intensity of the carrier is thus varied in accordance with background-illumination variations, these carrier variations cannot be used for the purpose of amplification control. Nor, as stated above, are there in this type of wave any synchronizing pulses which could be utilized for the purpose in question, since the signal is reduced to zero during the duration of line-retrace or line-synchronizing pulses. However, the modulation envelope includes a certain representative level, for example, the blanking level, at which the signal may represent black or blacker than black and which appears in the signal not only for black pictures, but also during the frame retrace periods. This level affords a measure of the intensity of the carrier wave which is independent of light modulation and of other signal characteristics, such, for example, as its periodicity or synchronization. This level may, therefore, be utilized automatically to control a characteristic of the receiver, such as its amplification.

In the operation of the present invention, therefore, the modulated-carrier wave is detected by the detector 15 to derive a voltage wave corresponding to the modulation envelope, which voltage is impressed upon the input electrodes of the stabilizing tube 20 by way of the non-conductive circuit including the grid condenser 23 and leak resistor 24. The grid condenser and leak serve to so vary the bias of the control grid, which, in the absence of a signal, is provided with zero bias, that the signal is stabilized; that is, to ensure that the peaks of the synchronizing pulses are at a substantially fixed level as impressed on the control grid. Where the connection between the control circuit and the detector is substantially a direct one, so that the unidirectional component of the signal is not lost, the signal may be sufficiently stabilized without the use of the stabilizing tube 20. However, where a nonconductive coupling intervenes between the detector and the control circuit, as in Fig. 1, the unidirectional

component is suppressed and the signal tends to center itself about the zero axis and to appear as illustrated by the curves of Fig. 3. In this case, therefore, it must be stabilized as explained.

The characteristics of the tube 20, also, are preferably such as to cut off or limit at least a part of the video-frequency portion of the wave, so that the wave form of the current in the anode circuit of the tube 20 is as illustrated by the wave forms of Fig. 4. Due to the time constant provided by the anode load circuit comprising resistor 25 and condenser 26, which is long compared with the duration of the line-synchronizing pulses and line-blanking intervals, but short compared with the field-blanking intervals, the voltage developed across the condenser 26 is not of the same form as the anode current, but is of the form shown in Fig. 5. In other words, the output circuit time constant is such as substantially to eliminate the effect of the line-synchronizing components and may be said to cause the system to ignore signal levels lower than that desired, for example, the line-synchronizing pulse level, because of their short duration, that is, the condenser 26 may be considered as by-passing the synchronizing pulses or components. The portions m, m' of the wave forms of Fig. 5 are representative of, and vary with, the signal level during the field blanking intervals. However, these portions are minima in the waves of Fig. 5 so that they cannot be measured directly.

In order to measure these voltage minima, there is obtained the difference voltage between the voltage across condenser 26 shown in Fig. 5 and the operating voltage or +B voltage, which difference voltage is developed across the resistor 25 with wave forms such as shown in Fig. 6. It is noted that this difference voltage has amplitude maxima p, p' corresponding to the minima m, m' of Fig. 5 and occurring during, and dependent solely upon, the blanking level during the field blanking intervals. This difference voltage, therefore, constitutes a control voltage which has a peak amplitude corresponding to variations in the average intensity of the received carrier and independent of light modulation, this being indicated at p and p' in Fig. 6 for the signals of different intensities. Moreover, the control signal is derived in response to a predetermined level of the modulation envelope occurring for a predetermined duration greater than the duration of a line-synchronizing pulse, in the present case, the blanking level, and independently of other characteristics thereof—particularly, independently of pulses dependent upon the periodicity of synchronization of the signal. This control signal is thereupon rectified by the peak rectifier or diode 21, thereby developing across its load resistor 27 a control-bias voltage dependent solely upon the portions p and p' of the waves of Fig. 5 while the difference voltage is as shown in Fig. 6, since operating potential is applied to the anode of diode 21 from the source +B by way of resistor 27, this potential is also on the control grid of the tube 22. A biasing battery is, therefore, included as shown in the cathode circuit of the tube 22 to compensate for the +B voltage. The difference or control-bias voltage is applied negatively to the grid of tube 22 wherein it is amplified with a reversal in polarity. This rectified and amplified control-bias voltage across the load resistor 29 of tube 22 is fairly steady and is proportional to the average intensity of the carrier and independent of light-modulation components. The filter comprising the resistors 30 and condensers

31 serves to remove residual fluctuations from the bias voltage. The resultant unidirectional-bias voltage is impressed negatively on the control electrodes of one or more of the tubes in the stages 12, 13, and 14 to control the amplification of these stages inversely in accordance with variations of the average carrier intensity and independently of light-modulation components. Thus, the output-signal intensity of the channel, including the stages 12, 13, and 14, is maintained within a relatively narrow range for a wide range of received signal intensities.

As explained above, the amplifier 22 simply serves to reverse the polarity of the unidirectional-bias voltage developed by the rectifier 21 to develop a voltage which increases negatively with increasing carrier amplitude and independent of light-modulation components. This is, of course, the required polarity for effecting automatic amplification control. Various other embodiments of the invention will be readily apparent to those skilled in the art, in some of which embodiments a reversing amplifier will be unnecessary. For example, the tubes 20 and 21 may be so connected that the voltage developed in the output circuit of the tube 21 increases negatively with increasing carrier amplitude, as by including a resistor equivalent to resistor 25 in the cathode circuit instead of the anode circuit of tube 20.

It will be noted that where the expression "wide range of signal-input intensities" is employed herein and in the appended claims, it refers to such intensity variations of the received carrier as are due to fading, to the different field strengths of different signals, and the like, and are independent of light-modulation components, and not to the normally smaller average carrier intensity variations which are caused by variation of the average background illumination.

It will be appreciated that the present invention may be utilized automatically to control various characteristics of a television receiver other than its amplification, for example, its selectivity or its tuning.

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A television receiver adapted for the reception of positively-modulated television signals including background components, synchronizing components, and video-frequency light-modulation components, comprising asynchronous control means responsive to a predetermined intermediate amplitude level of the modulation envelope of said signals and including a time-constant circuit for substantially eliminating the effect of said synchronizing components on the output thereof for developing a controlling effect, and means for utilizing said controlling effect for adjusting an operating characteristic of the receiver.

2. A television receiver adapted for the reception of positively-modulated television signals including background components, synchronizing pulses of a given type, and video-frequency light-modulation components, comprising asynchronous control means responsive to a pre-

determined intermediate amplitude level of the modulation envelope of said signals occurring for a predetermined duration greater than the duration of one of said synchronizing pulses and during any portion thereof for developing a controlling effect, and means for utilizing said controlling effect for adjusting an operating characteristic of the receiver.

3. A television receiver adapted for the reception of positively-modulated television signals including background components, synchronizing components, and video-frequency light-modulation components and having a predetermined blanking level, comprising asynchronous control means responsive solely to the blanking level of the modulation envelope of said signals and including a time-constant circuit for substantially eliminating the effect of said synchronizing components on the output thereof for developing a controlling effect, and means for utilizing said controlling effect for adjusting an operating characteristic of the receiver.

4. A television receiver adapted for the reception of positively-modulated television signals including background components, synchronizing components, and video-frequency light-modulation components and having a wide range of input intensities, comprising asynchronous control means responsive to a predetermined intermediate amplitude level of the modulation envelope of said signal and including a time-constant circuit for substantially eliminating the effect of said synchronizing components on the output thereof for developing a controlling effect, and means for utilizing said controlling effect to maintain the signal-output intensity of the receiver within a relatively narrow range.

5. A television receiver adapted for the reception of positively-modulated television signals including background components, synchronizing components, and video-frequency light-modulation components having a predetermined blanking level occurring during retrace periods and having a wide range of signal-input intensities, comprising a signal-amplifying channel, and asynchronous control means responsive to the blanking level of the modulation envelope of said signals and including a time-constant circuit for substantially eliminating the effect of said synchronizing components on the output thereof for developing a controlling effect, and means for utilizing said controlling effect to maintain the signal-output intensity of said channel within a relatively narrow range.

6. A television receiver adapted for the reception of a television signal carrier positively modulated during trace periods by background and video-frequency light components and unmodulated by light components during retrace periods and modulated by synchronizing pulses occurring during said retrace periods, comprising means for deriving the modulation envelope of said signal with the peaks of said synchronizing pulses thereof at a fixed level, asynchronous control means for developing a controlling effect from said modulation envelope variable in accordance with variations in a predetermined intermediate amplitude level thereof and including a time-constant circuit for substantially eliminating the effect of said synchronizing pulses on the output thereof, and means for utilizing said controlling effect to adjust an operating characteristic of the receiver.

7. A television receiver adapted for the reception of a television signal carrier positively modu-

lated during trace periods by background and video-frequency light components and unmodulated by light components during retrace periods with synchronizing pulses occurring during said retrace periods, comprising means for detecting said signal to derive the modulation envelope, means for stabilizing the detected signal to establish a fixed level for the peaks of said synchronizing pulses, asynchronous control means for developing a controlling effect from said stabilized detected signal variable in accordance with variations in a predetermined intermediate amplitude level thereof and including a time-constant circuit for substantially eliminating the effect of said synchronizing pulses on the output thereof, and means for utilizing said controlling effect to adjust an operating characteristic of the receiver.

8. A television receiver adapted for the reception of a television signal carrier positively modulated during trace periods by background and video-frequency light components and unmodulated by light components during retrace periods and having a predetermined blanking level with synchronizing pulses occurring during said retrace periods, comprising means for detecting said signal to derive the modulation envelope, means for stabilizing the detected signal to establish a fixed level for the peaks of said synchronizing pulses, asynchronous control means for developing a controlling effect from said stabilized detected signal variable in accordance with variations in the blanking level and including a time-constant circuit for substantially eliminating the effect of said synchronizing pulses on the output thereof, and means for utilizing said controlling effect to adjust an operating characteristic of the receiver.

9. A television receiver adapted for the reception of a television signal carrier positively modulated during trace periods by background and video-frequency light components and unmodulated by light components during retrace periods with synchronizing pulses occurring during said

retrace periods, comprising means for detecting said signal to derive the modulation envelope, a vacuum tube for stabilizing said detected signals having an input circuit non-conductively coupled to said detecting means and an output circuit having a predetermined time constant for substantially eliminating the effect of said synchronizing pulses to develop an asynchronous control signal from said stabilized detected signal variable in accordance with variations in a predetermined intermediate amplitude level thereof, a peak rectifier coupled to said output circuit for developing a unidirectional-bias voltage variable in accordance with variations in the peak amplitude of said control signal, and means for utilizing said bias voltage to adjust an operating characteristic of the receiver.

10. A television receiver adapted for the reception of a television signal carrier positively modulated during trace periods by background and video-frequency light components and unmodulated by light components during line and field retrace periods and having a predetermined blanking level with synchronizing pulses occurring during said retrace periods, comprising means for detecting said signal to derive the modulation envelope, a vacuum tube for stabilizing said detected signals having an input circuit non-conductively coupled to said detecting means and an output circuit having a predetermined time constant greater than the duration of said synchronizing pulses but less than the normal duration of said field retrace periods for developing an asynchronous control signal from said stabilized detected signal variable in accordance with variations in the blanking level thereof, a peak rectifier coupled to said output circuit for developing a unidirectional-bias variable voltage in accordance with variations in the peak amplitude of said control signal, and means for utilizing said bias voltage to adjust an operating characteristic of the receiver.

JOHN C. WILSON.
